F. K. KAYTE

ELECTRIC BULB

Filed Oct. 27, 1924

Frank K. Kayte,
INVENTOR
By Victor J. Evans

ATTORNEY

WITNESS:

UNITED STATES PATENT OFFICE.

FRANK E. KAYTE, OF FARR, COLORADO.

ELECTRIC BULB.

Application filed October 27, 1924. Serial No. 746,136.

My invention relates to electric illuminating bulbs and its primary object is the provision of an illuminating bulb which will give a maximum amount of light and at the same time increase the life of the bulb to a maximum.

The invention also provides an illuminating bulb having a plurality of filaments each of which is in an independent circuit 10 and so arranged as to enable one of the filaments to be brought into operation after the other has become burned out.

Still another object of the invention is to provide an illuminating bulb having a plurality of filaments each of which being arranged in an independent circuit together with a novel means for including one of the filaments in the circuit after the original filament has become burned out.

With the preceding and other objects and advantages in mind, the invention consists in the novel combination of elements, construction and arrangement of parts and operation, to be hereinafter specifically referred to, claimed and illustrated in the accompanying drawings, wherein:

Figure 1 is a vertical sectional view of an electric lamp bulb constructed in accordance with my invention.

Figure 2 is a horizontal sectional view taken on line 2—2 of Figure 1.

Figure 3 is a similar view taken on line 3—3 of Figure 1.

Figure 4 is a top plan view of the lamp.

Figure 5 is a perspective of the circuit closing element embodied in the invention.

Referring to the drawings in detail wherein corresponding characters of reference denote corresponding parts throughout the several views, the numeral 5 designates a porcelain or other non-conducting base to which the lamp bulb 6 is attached. The upper end of this lamp 6 is formed with an inwardly directed flange 7 which is drawn 40 to provide a hollow base 8 for a depending rod 9, the latter extending substantially the entire length of the bulb as shown. A threaded sleeve 10 is received on the base 5 and is adapted to be threaded in the usual 45 socket not shown.

Filaments 11 and 12 are carried by the post 9 and each of which includes vertically extending legs 13 and 14 that pass through the hollow base 8 and are connected to plugs

15 and 16 embedded in the base 5. A return wire 16^a for the filament 11 passes transversely through the side wall of the hollow element 8 and is connected as at 17 to the sleeve 10. A similar return wire 18 is provided for the filament 12 and which extends vertically through the base 5 and has one end normally disposed in semi-circular grooves 18' formed on the outer face of the base 5. When it is desired to bring this filament 12 into operation, this end of the wire 18 is connected to a laterally disposed lug 19 formed on the sleeve 10.

A conducting plate 20 normally rests in a shallow recess 21 in the upper face of the base 5 and receives a circuit closing disk 22, 70 the latter being provided with a pin or contact 23 engageable in either one of the plugs 15 and 16 to complete the circuit to either of the filaments above mentioned.

From an observance of Figure 2 it will be 75 noted that a circuit through the filament 12 is shown while the circuit through the filament 11 is interrupted as in the case when the same burns out.

While I have shown and described the 80 preferred embodiment of the invention, I desire to have it understood that such changes in the form, construction and arrangement of parts may be made as will not depart from the spirit of the invention or the scope 85 of the subjoined claim.

What is claimed is:

An electric light comprising a bulb, a non-conducting base to which the bulb is attached, a metallic sleeve on the base, a 90 conductor plate carried by the base, sockets embedded in the base beneath the conductor plate, the ends of said sockets being spaced inwardly from the end of the base, a pair of filaments, each of which has one terminal 95 connected with a corresponding socket and one of which has its other terminal connected to the sleeve, the remaining terminal being adapted to be connected to the sleeve in the event that the filament which is terminally connected becomes inoperative, a 100 circuit closing disk contacting with the plate, a pin carried thereby and engageable in either of the sockets whereby the circuit may be completed to either of the filaments. 105

In testimony whereof I affix my signature.

FRANK E. KAYTE.
